UNITED STATES PATENT OFFICE.

ROBERT J. CLARKE, OF PITTSBURG, PENNSYLVANIA.

WINDOW-CLEANING DEVICE.

No. 849,204.

Specification of Letters Patent.

Patented April 2, 1907.

Application filed December 13, 1906. Serial No. 347,630.

To all whom it may concern:

Be it known that I, ROBERT J. CLARKE, a citizen of the United States of America, residing at Pittsburg, in the county of Allegheny and State of Pennsylvania, have invented certain new and useful Improvements in Window-Cleaning Devices, of which the following is a specification, reference being had therein to the accompanying drawings.

This invention relates to window-cleaning devices; and the invention has for its object to provide a novel attachment for street-cars for cleaning the window in front of the motorman or operator of the car, said device embodying positive and reliable means that can be easily actuated by the motorman or operator of the car to remove frost, snow, or water that would tend to interfere with the transparency of the window.

Another object of this invention is to provide a window-cleaning device that can be readily used upon the windows of various kinds of vehicles or cars, such as Pullman cars, the device being constructed whereby it can be easily and quickly manipulated at any desired time.

With the above and other objects in view, which will more readily appear as the invention is better understood, the same consists in the novel construction, combination, and arrangement of parts to be hereinafter more fully described and then specifically pointed out in the appended claim.

Referring to the drawings forming part of this specification, like numerals of reference designate corresponding parts throughout the several views, in which—

Figure 1 is a front elevation of a street-car equipped with my improved window-cleaning device. Fig. 2 is a vertical sectional view taken on the line $x-x$ of Fig. 1. Fig. 3 is a similar view taken on the line $y-y$ of Fig. 1. Fig. 4 is a fragmentary elevation of a portion of a car, illustrating one of the guides. Fig. 5 is a perspective view of a portion of one of the guides. Fig. 6 is a detail perspective view of a portion of a movable rod used in connection with the window-cleaning device. Fig. 7 is a cross-sectional view of the same. Fig. 8 is a vertical sectional view of a portion of my improved device, illustrating a slight modification in the construction thereof; and Fig. 9 is an elevation of a window equipped with my improved device, illustrating a modified form of actuating means.

To put my invention into practice, I provide the side rails 1 of a window 2 with vertically-disposed channel-shaped guides 3, these guides being secured to the outer sides 60 of the rails 1. In the guides are mounted movable blocks 4, carrying a transverse rod 5, in which is secured a scraper 6 or piece of resilient cleansing or abrasive material, as rubber, metal, carborundum, felt, or leather. 65 The scraper is adapted to engage the window 2, and in order that the entire surface of the window may be cleaned of any foreign matter that would tend to obliterate a person's vision through the same I provide novel 70 means for moving the scraper over the window. Attached to the blocks 4 are flat band-springs 7, normally maintained under tension in a suitable casing 8, carried upon the inner side of the window 2, said springs passing 75 through slots 9, formed in the rails 1 at the upper ends of the guides 3. The flat band-springs 9 are adapted to retain the scraper at the top of the window 2, and to lower the same I attach cables 10 to the blocks 4, said 80 cables passing over sheaves 11, carried by the sill of a window, and extending through the framework 12 beneath the window and having their ends connected together upon the inner side of the window, whereby a person 85 pulling upon the cables 10 can easily lower the scraper to remove foreign matter from the window 2. Upon releasing the cables the band-springs 9, which have been placed under tension, are adapted to return the scraper 90 to its normal position at the top of the window.

The application of the device just described to a street-car is clearly illustrated in Figs. 1 to 4, inclusive, of the drawings, and in 95 this instance the operator or motorman of a car manipulates the device to remove frost, snow, or water that may adhere to the window 2 therefrom.

In Fig. 8 of the drawings I have illustrated 100 a slight modification of my improved window-cleaning device wherein the cables 10 are dispensed with and the rails 1 provided with slots 14. The blocks 4 are provided with rearwardly-extending arms 15, which 105 protrude through the slots 14 and are provided with handles 16. It is only necessary to grip the handles and move them toward the bottom of the window to cleanse the same, the flat band-springs 9 returning the 110 scraper to its normal position.

A still further modification is illustrated in

Fig. 9 of the drawings, wherein I dispense with the handles 16 and provide the block-arms 15^a with cables 10^a, said cables being attached to drums 17, revolubly mounted in the framework of the window. Each drum carries a pinion 18, adapted to mesh with a movable rack 19, said rack being carried in guides 20 and provided with a handle 21, which is moved to rotate the drums 17 and wind the cables thereon. In this manner the scraper can be drawn downwardly over the window similar to the cables 10 or the handles 16 where used. The construction shown in Fig. 9 of the drawings is particularly adapted for Pullman cars or vehicles where neat window-fixtures are necessary. It is obvious that the window-framework must be provided with a horizontal slot to permit of the handle 21 protruding therethrough, the slot being of sufficient length to allow the handle to be moved therein to lower the scraper of my improved device.

Such changes in the size, proportion, and minor details of construction as are permissi-

ble by the appended claim may be resorted to without departing from the spirit and scope of the invention.

What I claim, and desire to secure by Letters Patent, is—

In a window-cleaning device, the combination with a window-frame of channel-shaped guides secured to the frame, slide-blocks in said guides, a rod carried by said slide-blocks, a wiper carried by said rod, a casing at the upper end of said window-frame, band-springs in said casing having one end of each spring extended through an opening provided therefor in the frame and connected to said rod, and means connected to said slide-blocks for actuating the same, substantially as described.

In testimony whereof I affix my signature in the presence of two witnesses.

ROBERT J. CLARKE.
